UNITED STATES PATENT OFFICE.

JOHN FRANKLIN BERRY, OF LEWIS, IOWA.

INTERNAL-COMBUSTION ENGINE.

1,258,524.

Specification of Letters Patent.

Patented Mar. 5, 1918.

Application filed November 2, 1915. Serial No. 59,242.

To all whom it may concern:

Be it known that I, JOHN FRANKLIN BERRY, a citizen of the United States, residing at Lewis, in the county of Cass and State of Iowa, have invented new and useful Improvements in Internal-Combustion Engines, of which the following is a specification.

This invention relates to internal combustion engines and has particular reference to the valve mechanism thereof, the object in view being to produce a valve which may constitute either the intake or the exhaust valve, which valve is of tubular construction and mounted for reciprocatory movement in parallel relation to but exteriorly of the combustion chamber of the engine, operating to periodically open and close the cylinder port leading to or from the combustion chamber of the engine.

A further object of the invention is to provide a valve of the character referred to embodying a novel wall construction by means of which it is properly lubricated and cooled, the valve being constantly in communication with the crank case.

With the above and other objects in view, the invention consists in the novel construction, combination and arrangement of parts, as herein described, illustrated and claimed.

In the accompanying drawings:—

Figure 1 is a sectional view taken longitudinally and diametrically of the cylinder and piston and transversely of the crank shaft.

Fig. 2 is a cross section on the line 2—2 of Fig. 1.

Fig. 3 is an enlarged fragmentary longitudinal section through one of the valves and the adjacent portion of the cylinder.

Fig. 4 is a side elevation of the valve.

Referring to the drawings A designates generally the cylinder of an internal combustion engine and B the crank case thereof. The cylinder wall being water jacketed as shown at 1 and the cylinder head being also water jacketed as indicated at 2.

The crank case B is provided with the usual supporting lugs 3 and a horizontally extending partition 4 which divides the crank case into an upper chamber 5 and a lower chamber 6 the latter constituting the oil chamber, and the partition 4 being formed with a pocket or sink 7 for each cylinder, the pocket 7 being designed to con-

tain oil into which the crank of the respective cylinder dips for the usual purpose.

8 designates a reciprocating piston working in the combustion chamber 9 and coupled by means of a connecting rod 10 to the crank shaft 11.

In carrying out the present invention, the body of the cylinder which is formed with inlet and exhaust ports 12 and 13, respectively, at diametrically opposite points, is also formed with valve containing cylindrical bores or chambers 14 located exteriorly of the combustion chamber and in parallel relation thereto but out of communication therewith except for the diametrically opposite ports 15 and 16 which are in line with the intake and exhaust ports 12 and 13, respectively as clearly indicated in Fig. 1.

In each of the valve bores 14 is mounted a reciprocating tubular valve, 17 designating the intake valve and 18 the exhaust valve, said valves being the counterpart of each other. Reciprocating motion is imparted to the valves 17 and 18 by means of valve shafts 19 and 20 located at opposite sides of the crank shaft 11 and driven thereby through the medium of the gears 21, 22 and 23, said gears being shown as proportioned to render the engine of the four cycle type, the valve or cam shafts 19 and 20 revolving at one-half the speed of the crank shaft 11.

Each of the valves 17 and 18 is closed at its outer end by an end wall or head 23' and the inner end thereof is left open as at 24 so that the interior of the tubular valve is in constant communication with the crank case for cooling and lubricating purposes. Adjacent to its outer end each valve is provided with a passage 25 the length of which is disposed transversely of the tubular valve, the passage 25 being itself formed by a tube 26 extending through the valve and having the opposite extremities thereof united by a fluid tight joint to the opposite side walls of the valve. The valve wall is also formed with openings 27 shown in the form of perforations of a considerable number extending throughout the major portion of the length and all around the valve wall, said openings permitting the oily vapor within the crank case to pass therethrough and keep the outside surface of the valve wall and the inner surface of the valve bore perfectly lubricated. In addition to this

the valve body is kept at a uniform temperature corresponding approximately with the temperature in the crank case thereby preventing undue expansion of the valve body 5 and the consequent liability of the same to bind within the bore in which it operates.

In order to prevent leakage around the valve between the ports 12 and 15 and also between the ports 13 and 16, the body of the 10 cylinder is formed with annular grooves 28 at opposite sides of the line of said ports and packing rings 29 are seated in said grooves, being held in place therein and encircling and contacting throughout their 15 inner peripheries with the respective valve body. The valve bores 14, as shown in Fig. 1, intersect the intake and exhaust ports of the cylinder and the outer end portions of the valve work across said ports and points 20 of intersection and thereby always have a bearing against the packing rings 29 so as to effectively prevent leakage and loss of compression.

The valves 17 and 18 are coupled by 25 means of connecting rods 30 to the shafts 19 and 20, said shafts being shown as provided with eccentrics 31 which operate in straps or bearings 32 on the ends of the rods 30.

It will, of course, be understood that the 30 shafts 19 and 20 with their eccentrics 31 are set so as to properly time the reciprocatory movements of the intake and exhaust valves in order that the usual cycles of 35 operation of the engine may be carried out and the explosive mixture admitted at the proper time and the burned gases exhausting at the proper time. The construction described does away entirely with the use

of puppet valves and the disadvantages incident to the use thereof such as the rapid accumulation of carbon around the valve seats, greatly impairing the efficiency of the engine; the valve openings or ports are practically noiseless in their operation as a sliding contact only is obtained, and a maximum impulse is obtained by reason of the fact that each charge is confined directly and only in the combustion chamber and fired when under full compression where it 50 acts with full effect directly between the head of the piston and the inside wall of the cylinder head.

Having thus described my invention, I claim:—

In a reciprocatory internal combustion engine, a cylinder formed with a cylindrical bore located exteriorly of the combustion chamber, parallel thereto and intersecting a cylinder port and also in open communication with the crank case, in combination with a tubular reciprocatory valve working in said bore and in open communication throughout its length with the crank case, and provided with a passage extending 65 transversely through the same and movable into and out of registry with said cylinder port, the tubular valve and the bore in which it works being both closed at the upper ends thereof, said valve being formed with lubricant openings through its side walls.

In testimony whereof I affix my signature in presence of two witnesses.

JOHN FRANKLIN BERRY.
